ARY C. CLARK AND ARTHUR L. GRAVES, OF IMPERIAL, CALIFORNIA; SAID GRAVES
ASSIGNOR TO IMPERIAL IRRIGATION DISTRICT, A CORPORATION OF CALIFORNIA

EXCAVATOR

Original application filed September 12, 1928, Serial No. 305,450. Divided and this application filed November 29, 1929. Serial No. 410,458.

Our present invention relates to excavators, or diggers, for making and maintaining canals or ditches for irrigation purposes.

This application is a divisional application of our copending application for digging bucket construction for excavators, filed September 12th, 1928, Serial No. 305,450.

The objects of our present invention are: first, to provide an excavator or digger of this class having a very flexibly mounted and readily shiftable excavating portion; second, to provide a machine of this class which has particularly large capacity and which is very efficient, particularly in that the materials excavated or dug are easily, rapidly and efficiently dumped or discharged; third, to provide a machine of this class in which the greatest simplicity of construction, strength, and efficiency are incorporated; fourth, to provide a digging bucket conveyer having buckets from which all or the greater portion of the materials excavated or dug are dumped clear of the machine to the side of the canal or ditch and from which the remaining materials are discharged at substantially the same place when and as the buckets continue over their circuitous path; fifth, to provide supporting means for the digging buckets whereby the buckets are dumped without auxiliary means to aid in the dumping or discharging of the contents of the buckets; sixth, to provide as a whole a novel mounting of such self-dumping buckets on digging conveyers; seventh, to provide a novel arrangement of guiding and driving pulleys or sprockets for the bucket conveyer whereby the above functions are effectively carried out; and, eighth, to provide a machine of this class which is simple and economical of construction proportionate to its functions, one which is easy to operate and one which will not readily deteriorate or get out of order.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference

thereon which form a part of this application in which:

Figure 1 is a rear elevational view of our canal excavator or digger in its preferred form of construction; Fig. 2 is an enlarged sectional elevational view, showing a fragmentary portion of our bucket conveyer extended around one of the supporting and guiding wheels and showing one of the buckets in the main discharging position, the section being taken through the longitudinal center of the bucket conveyer; Fig. 3 is a fragmentary sectional view thereof taken at 3-3 of Fig. 2 looking into the bucket from the front side thereof, and Fig. 4 is a fragmentary view of the bucket showing its relation to the supporting conveyer, the view being taken at 4-4 of Fig. 2 looking into the bucket from the inner open side thereof, certain portions being broken away and in section to facilitate the illustration.

Like characters of reference refer to similar parts and portions throughout the views of the drawings.

The main frame, designated 1, of our excavator is mounted at its opposite sides on tractors 2 and 3, the latter being extendable laterally from the main portion of the main frame. Beyond the rear end of the main frame 1 is mounted the excavator or the excavating portion of the machine. The excavating portion of the machine is mounted on a frame 4 which is primarily and loosely and pivotally mounted at one end, preferably at its extreme upper end, on the main frame 1. For so supporting the frame 4, there is provided an upright support 5 at the rear portion of the frame 1 and which is provided at its upper end with a backwardly extending beam 6 carrying a plurality of sheaves 7. Around these sheaves 7 and another sheave 8 extends a cable 9 for supporting and adjusting the elevation of the frame 4. The sheave 8 is pivotally mounted on a supporting member 10 which is pivotally connected at its lower end on a transverse axis to the pivotal supporting member 11. This pivotal supporting member 11 is pivotally connected by a pivot shaft 12 to pivot bearings 4a at the upper end of the frame 4, as shown in Fig. 1.

The pivot shaft 12 is preferably extended forwardly to the main frame of the machine and is connected to a guide member 13 which is adapted to ride upwardly and downwardly on the vertical column 5a of the supporting frame 5. The shaft 12 is therefore adapted to prevent the whole of the frame 4 from swaying forwardly and backwardly as a body. The connection of the shaft 12 to the 10 guide member 13 is preferably by a universal joint connection (not shown).

At the opposite side of the main frame 1 is provided a boom 14 from the extended end of which the free, normally lower end of the 15 excavating frame 4 is supported and by which the latter frame is raised and lowered about the pivotal axis of the shaft 12.

The frame 4, in this instance, is provided with a substantially rectangular upper portion 4b and a downwardly extending angular leg 4c which extends toward the middle portion of the machine, that is, between the tractors 2 and 3. At the outer side of the portion 4b of the excavating frame are mounted a 25 pair of spaced apart conveyer drive sprockets 15 which may be driven by any suitable means, such as by a power unit 26 mounted on the frame 4. Around these sprockets extend the continuous or endless link belts 16 30 which also extend around spaced apart flanged wheels 17 at the inner side of the frame 4, around other spaced apart flanged wheels 18 at the lower end of the angular leg 4c of the frame 4, and then around a portion 35 of the inner side of a dumping wheel which consists of a pair of flanged wheel members 19 spaced axially from each other and mounted on a unitary shaft. Said dumping wheel is positioned intermediate the drive sprockets 40 15 and the flanged wheels 18 and adjacent the former. These flanged members 19 are preferably of larger diameter than the other flanged wheels. The portions of the link belts 16 extending from the dumping members 19 45 to the sprockets 15 are preferably inclined downwardly and outwardly so that the buckets 20 carried by the link belts are correspondingly tilted as the same pass over the dumping wheel and along the inclined portions of the belt. It will be here noted that 50 the extreme tilting of the buckets takes place while the buckets are substantially supported by the wheel members 19.

The buckets 20 are preferably of thin shells 55 having lateral side walls 20a, a bottom wall 20b inclined backwardly and inwardly, and a back wall 20c. Both the front side and the inner side, that is, the side opposite the bottom wall 20b, are open, as shown best in Figs. 60 2, 3 and 4. The front edges of the bottom wall and the side walls are reenforced and turned outwardly to facilitate the digging operation.

These buckets are positioned in relatively 65 close relation to each other and supported on

and between the pair of spaced apart continuous conveyer belts 16 which are in the form of link belts and which ride, except for the drive sprockets 15, upon the several pairs of wheels 17, 18 and 19, which are flanged wheels, as shown best in Figs. 2, 3 and 4. The link belts, in this instance, are made up of U-shaped links 16a, the ends of the legs of one link extending to the opposite sides of the connecting portion of the legs of the next link and are pivotally connected in such relation by belts or rivets. Some of the links are provided at the inner sides of the ends of their legs with inwardly extending bosses 16b upon which the forward and inner portions 70 of the buckets are pivotally mounted. For pivotally connecting and mounting the buckets on the link belts, we have provided brackets 21 which are secured to the outer sides of the side walls 20c and near their inner edges, as shown in Figs. 2, 3 and 4. The forward ends of these brackets are provided with bosses 21a which extend around the bosses 16b of the links. The bosses 21a are retained in pivotal relation on the bosses 16b by the bolts 22 which also serve as the pivotal connection of the links provided with the boss 16b and the links positioned between the legs of the former. The brackets 21 extend beyond the rear portions of the buckets and are provided with longitudinal slots 21b, the slots being substantially parallel to the upper or inner edges of the corresponding buckets. The opposite sides of the slots 21b, that is, the walls forming the opposite sides of such slots, are straight and flat while the ends of the slots are beveled inwardly from the opposite side of the slotted portion, as indicated by 21c in Figs. 2 and 4. The link belts 16 are provided with other links having bosses 16c, the latter links being positioned several links back of those having the bosses 16b. The bosses 16c are constructed similar to the bosses 16b and have the same relation to the links of the link belt conveyer. The bosses 16c extend through the slots 21b and are adapted to slide therein, said bosses being retained in position with respect to the brackets 21 by bolts 24 which extend through the bosses 16c and also serve 80 as the pivotal connection of the links provided with the bosses 16c and the links positioned forwardly thereof or between the legs of the former. Between the heads or nuts of the bolts 24 and the inner sides of the brackets 21, are positioned washers 23 which engage the inner sides of said brackets adjacent said slots.

Thus, if any mud or other materials are caught in the slots 21b, the mud may be forced between the ends of the slots and the bosses 16c and is automatically ejected by the inclined walls at the ends of the slots. The purpose of the slots 21b is to permit the bucket to be securely supported at all times 95 100 105 110 115 120 125 130

upon the link belt as the same ride around the several drive sprockets and supporting wheels without necessitating the use of innumerable links or complicated mechanism for yieldingly supporting the buckets on the link belts as the same pass around their multi-curved circuitous paths.

As the buckets pass between the wheel members 19, the same are substantially tilted, as shown, causing all or the greater portion of the contents of the buckets to be discharged to the side of a ditch dug or cleaned. If any materials remain in the bucket, the same are carried around the drive sprockets and dumped through the inner opening of the bucket as the bucket is instantly leveled out after passing the upper portion of the drive sprockets, the discharge of the remaining materials being at substantially the same place as the formerly discharged material.

Though we have shown and described a particular construction, combination and arrangement of parts and portions, we do not wish to be limited to this particular construction, combination and arrangement, but desire to include in the scope of our invention the construction, combination and arrangement substantially as set forth in the appended claim.

Having thus described our invention, what we claim as new and desire to secure by Letters Patent is:

In an excavator of the class described, an excavator frame, a plurality of conveyer belt supporting wheels revolvably mounted on said frame, one wheel being mounted at the lower excavating end of the frame, a second wheel being mounted at the upper and opposite end of said frame, and a dumping wheel mounted between the two first mentioned wheels and adjacent the second wheel, a conveyer belt extending around the outer portions of the first wheel and around the inner portion of the dumping wheel, the portion of the belt extending between the second and the dumping wheels extending substantially outwardly, and a plurality of digging buckets mounted in spaced relation on said belt, said buckets being directly pivotally and slidably mounted on said belt and adapted to discharge the contents thereof when passing over said dumping wheel, said dumping wheel comprising a pair of axially spaced wheel members mounted on a shaft, said buckets passing between the wheel members and around and over the shaft when passing over the dumping wheel.

In testimony whereof, we have hereunto set our hands at Los Angeles, California, this 20th day of November, 1929.

ARTHUR C. CLARK.
ARTHUR L. GRAVES.
